UNITED STATES PATENT OFFICE.

EDWARD OVERMAN, OF LOS ANGELES, CALIFORNIA.

LAND LEVELER.

Application filed December 22, 1927. Serial No. 241,910.

This invention relates to drag scrapers or levelers, and particularly levelers of that type in which a cutting and scraping blade is mounted upon a supporting frame, the scraping blade acting to scrape off or slice off high places and conveying the material so cut off to low places in the roadway or other ground being scraped.

The general object of the present invention is to provide a device of this kind which includes a supporting frame, a blade, and means acting automatically and disposed forward of the blade whereby the blade may be caused to cut deeper into the ground whenever the blade comes to a high place and which acts to cause the blade to carry the earth so cut off along over the surface of the ground until a low place is met with, whereupon the blade is dis-

20 charged.

A further object is to provide means whereby the blade may be raised or lowered as desired by hand and whereby this raising of the blade will cause the frame to move along on rollers with the blade above the surface of the ground.

Another object is to provide means whereby the blade may be manually shifted or tilted from a position of less cut to a position of greater cut.

Other objects have to do with the details of construction and arrangement of parts as will appear more fully hereinafter.

My invention is illustrated in the accompanying drawings, wherein:—

Figure 1 is a top plan view of the drag scraper constructed in accordance with my invention;

Figure 2 is a section on the line 2—2 of Figure 1;

Figure 3 is a like view to Figure 2 but showing the scraper raised;

Figure 4 is a like view to Figures 2 and 3 but showing the body of the scraper entirely raised for traveling.

Referring to these drawings, it will be seen that the frame of my improved land leveler consists of the upper and lower longitudinally extending, laterally spaced angle irons 10 and 11. These may be angle irons or T-irons or may be channel irons. These irons 10 and 11 are held in spaced relation by the vertical members or webs 12, which may also be of any suitable construction.

55 A platform 13 is mounted upon the upper

pair of angle irons 10 adjacent the rear end thereof, and this platform is supported by the cross pieces or braces 14 and 15. An upwardly curved cross piece or brace 16 is provided at the forward end of the machine. A detachable runner iron 18 is bolted or otherwise attached to each of the longitudinal members 11. The runner iron 18 and the angle iron 11 constitute runners, each runner being turned upward at its forward end and at its rear end extending upward and rearward and supporting a bearing for a shaft 19 upon which are mounted the rollers 20 or wheels. These rollers are so supported that they are on a level with the sled runner. Mounted upon the rails or beams 10 are the forwardly converging irons 21 upon which any suitable draft device 22 may be mounted.

Mounted between vertical webs 23 forward of the platform 13 is an arcuate scraper blade 24. This scraper blade has wings or end pieces 25 and these are pivotally mounted upon the brace. As illustrated, this pivot consists of a transverse shaft 26 but I do not wish to be limited to this.

It will be noted that the pivotal axis for the wings 25 and for the scraper blade is not concentric to the scraper blade but eccentric thereto. Loosely mounted upon the shaft 26 is a forwardly converging frame 27, which at its forward end carries the two easter wheels 28. This frame oscillates with the scraper. Attached to the scraper and extending over the shaft 26, if a shaft 26 is used, is a tongue 29 which extends upward and forward and over the forward end of the U-shaped frame 27, and passing through the tongue and connecting this tongue to the frame is a wing bolt 30 and 95 between the tongue and the frame and around the bolt is disposed the coiled compression spring 31. The scraper blade is provided upon its rear face with the outwardly projecting arm 32 which is connected by a link 33 to a lever 34, this lever being pivoted upon an ear 35 at the rear end of the machine and being urged downward by a spring 36 which surrounds a pedal 37 which extends up through the platform 13.

Mounted in bearings upon the forward edge of the platform 13 is a crank shaft 38 having a handle 39 whereby it may be manipulated, the crank of this shaft being con-

nected by a link 40 to a lever 41 which is pivotally mounted upon ears on the forward cross bar of the supporting frame. This lever 41 bears against the upper face of the tongue 29 and when the lever 39 is drawn rearward the lever 41 will be depressed, thus forcing downward upon the forward end of the tongue 29 and forcing the wheel frame 27 downward and the scraper upward.

10 The general operation of this device, assuming that the lever 39 is shifted forward, is as follows: As the machine moves over the ground the caster wheels 28 will also move over the ground so that in going 15 over a high place on the surface of a field or road these caster wheels at the front end of the frame 27 will lift this frame at this end and depress the cutting blade so that the cutting edge of the cutter will go deeper 20 into the ground, thus cutting off the high place. The cutter will remain in this position and will carry the earth so cut off along until the frame 27 comes to a low place or depression in the field. The wheels of this 25 controlling frame will then move downward and this will rotate the cutting blade upward and rearward, thus allowing the accumulated earth to be released or discharged into the hollow or depression and thus filling up the 30 low place.

The sled or drag-like body of the leveling device is to be of sufficient length to insure its remaining on a reasonably level plane at all times so that the body of the device will 35 bridge over small ruts and inequalities, the cutter, however, being raised or depressed automatically by these inequalities in the ground. The foot pedal 37 is used to assist in holding the cutter into the ground at hard 40 places or holding the cutter down when it is desired to carry the accumulated dirt or soil over low places in the field. The compression spring which surrounds the foot pedal is for the purpose of counterbalancing 45 the weight of the controlling frame 27 and its rollers. The lever 39 is for the purpose of manually regulating the leveling device. If this lever is pulled back, the lever 41 will force down the tongue 29, which will force 50 down the controlling frame 27 and thus the front end of the sled is lifted and the whole leveling device will be carried on the casters at the front end and the rollers at the rear end. By the same operation the cutter 55 is also lifted so that the whole apparatus may be turned at the ends of a field or road or over a large depression in the field that needs to be filled in, or the apparatus may be drawn to or from the field to be leveled. It 60 is to be particularly noted that the blade is eccentrically pivoted, as before stated, and thus when the blade is turned completely downward it will tend to carry the earth from one place to another, and when the controlling frame or truck moves downward the

blade will be turned into a discharge position.

It will be seen that this device is very simple, that it is very strongly constructed, and that it is particularly effective for the purpose described. The frame is sufficiently long so that it does not travel into holes or ride over humps or projecting portions of the ground but that it is the scraper which is automatically raised or lowered to cut off 75 and fill up inequalities.

Attention is particularly called to the fact that the truck frame 27 is not directly connected to the scraper 24 or to the ends 25 of the scraper but that this frame 27 is loose upon the shaft 26. This is for the reason that it is necessary to provide means for adjusting the cutting edge of the scraper to the proper level of the runners so that the scraper will neither cut too deeply or too 80 slightly, as in cutting too deep too great a load would be carried and if not deep enough the scraper would pass over the lumps without removing them. To this end, as I have illustrated, I have pivotally connected the controlling frame to shaft 26 to permit this frame 27 to oscillate independently of the oscillation of the scraper and I have operatively connected the controlling frame 27 to the scraper by means of the tongue 29. This

tongue is connected to the controlling frame 27 by means of the bolt 30 with the wing nut. The controlling frame 27 and the tongue are separated by the compression spring 31 through which the wing bolt or screw 30 passes. Assuming that the casters of the controlling frame 27 are at the level of the runners 11 and 18 and the wing nut 30 is screwed down fully, then the cutting edge of the scraper 24 will be raised above the 105 level of the runners 11 and the humps passed over, but when the wing screw 30 is fully unscrewed the cutting edge of the blade will be below the level of the runners 11 and cut too deeply, but by properly adjusting the wing screw 30 and the compression spring 31, the proper adjustment can be obtained. After this adjustment is obtained, any variation in height of the caster wheels 110 will cause a like variation in the tongue 29 and thus cause the oscillation of the blade 115 24.

I do not wish to be limited to the construction shown in Figure 2, as it is possible to use an adjustable cutting blade on the scraper and obtain the same results, and under those circumstances the tongue 29 may be omitted and the frame 27 connected rigidly to the shaft 26 or to the scraper. The means which I have employed, however, permit the very ready adjustment of the cutting blade relative to the controlling tongue. The basic principle of my device rests in the automatic controlling of the scraper by means of a controlling device (27) which

follows the contour of the ground by means of wheels, a drag or a runner, and it will be understood, therefore, that I do not wish to be limited to the use of the wheels 28.

5 While I have illustrated certain details of construction and arrangement of parts, I do not wish to be limited to these as many changes might be made without departing from the spirit of the invention as defined 10 in the appended claims.

I claim:—

1. A land leveler of the character described comprising a supporting frame, a scraper pivoted upon the frame for downward and forward movement, and a ground engaging controlling member operatively connected to the scraper and disposed in front of the pivotal center thereof and acting to lift the scraper as the controlling member lowers and depress the scraper as the controlling member is raised.

2. A land leveler of the character described comprising a supporting frame, a scraper pivotally mounted upon the frame for downward and forward bodily movement in an arc of a circle, and a ground engaging controlling member operatively connected to the scraper to oscillate therewith and disposed in front of the pivotal axis 30 of the scraper, said controlling member having a ground engaging wheel.

3. A land leveler of the character described comprising a supporting frame, a scraper pivotally mounted upon the frame for downward and forward bodily movement in an arc of a circle, and a ground engaging controlling member operatively connected to the scraper to oscillate therewith and disposed in front of the pivotal axis of 40 the scraper, said controlling member including an approximately U-shaped frame having caster wheels attached thereto.

4. A land leveler of the character described comprising a supporting frame, a scraper pivotally mounted upon the frame for downward and forward bodily movement in an arc of a circle, a ground engaging controlling member operatively connected to the scraper to oscillate therewith and disposed in front of the pivotal axis of the scraper, said controlling member including an approximately U-shaped frame having 50 caster wheels attached thereto, and a tongue attached to the scraper and extending over the forward end of the U-shaped frame and operatively connected thereto.

5. A land leveler of the character described, including a supporting frame, a curved scraping blade having forwardly projecting end pieces and pivotally mounted upon the frame on an axis extending through the end pieces and eccentric to the curved blade, and ground engaging means disposed in advance of the axis of the blade and 65 operatively connected to the blade to cause

the blade to rise when the ground engaging means is depressed and to fall as the ground engaging means is raised.

6. A ground leveler of the character described comprising a supporting frame, an arcuately curved blade mounted upon the frame and having forwardly projecting wings, the wings being operatively pivoted to the frame on an axis eccentric to the blade, a controlling truck operatively connected to said wings and extending in advance thereof and having ground engaging wheels, a tongue operatively connected to the blade and extending forward and over the controlling truck and operatively connected thereto, a lever mounted upon the forward end of the frame, the lever when turned in one direction being adapted to be engaged with said tongue to depress the same, and a manually operable lever mounted upon the supporting frame for actuating the first named lever.

7. A ground leveler of the character described comprising a supporting frame, an arcuately curved blade mounted upon the frame and having forwardly projecting wings, the wings being operatively pivoted to the frame on an axis eccentric to the blade, a controlling truck operatively connected to said wings and extending in advance thereof and having ground engaging wheels, a tongue operatively connected to the blade and extending forward and over the controlling truck and operatively connected thereto, a lever mounted upon the forward end of the frame, the lever when turned in one direction being adapted to be engaged with said tongue to depress the same, a manually operable lever mounted upon the supporting frame for actuating the first named lever, a bolt connecting the tongue with the truck frame, and a spring disposed between the truck frame and the said tongue.

8. A ground leveler of the character described comprising a supporting frame including two laterally disposed runners, the rear ends of the runners being upwardly turned, a shaft having wheels mounted upon the rear ends of the runners, a scraper blade pivotally mounted between said runners for downward and forward swinging movement, a nut controlling truck operatively connected to said scraper blade and extending in advance thereof between said runners and having ground engaging wheels, and manually operable means adapted to force the forward end of said truck downward to thereby depress the wheels and raise the supporting frame upon said forward wheels and the rear wheels.

9. A ground leveler of the character described including a supporting frame having laterally disposed runners, an arcuately curved blade disposed between the runners

and having forwardly extending wings operatively pivoted to the runners on an axis eccentric to the curvature of the blade, a ground engaging truck frame operatively connected to the wings and scraper blade at its rear end and having ground engaging wheels at its forward end whereby to automatically control the depth of cut, and a lever operatively connected to the scraper blade and having a pedal whereby the lever may be depressed.

10. A leveler of the character described comprising a supporting frame formed of upper and lower longitudinally extending angle irons, vertical webs connecting the angle irons and transverse members connecting the upper angle irons on each side, sled runners attached to the lower angle irons and projecting beyond the same at each end, the rear ends 15 of said runners supporting wheels, draft devices applied to said frame, an arcuately curved blade having wings at its ends and disposed on said frame between the runners, a shaft eccentric to the curvature of the 20 blade mounted upon the sides of the frame and extending through the wings, a U-shaped controlling truck frame mounted upon said shaft and operatively connected to the ends of the blade, caster wheels secured 25 to the forward end of the controlling frame, a tongue attached to the blade and to said shaft and extending over the forward end of the controlling frame and operatively connected thereto, means for manually depressing 30 the forward end of the controlling frame, and means for manually depressing the blade 35 and lifting the controlling frame.

11. A land leveler of the character described comprising a supporting frame, a 40 scraper mounted upon the frame for downward or upward movement, and ground engaging controlling means operatively connected to the scraper and disposed in front of the pivotal center thereof and acting to 45 lift the scraper as the controlling means lowers and depress the scraper as the controlling means is raised.

12. A land leveler of the character described comprising a supporting frame, a scraper mounted upon the frame for downward or upward movement, ground engaging controlling means operatively connected to the scraper and disposed in front of the pivotal center thereof and acting to lift the scraper as the controlling means lowers and depress the scraper as the controlling means is raised, and means for adjusting the scraper relative to the ground engaging member.

13. A leveler of the character described comprising a supporting frame, an arcuately curved blade mounted upon the frame for downward and forward swinging movement, a controlling truck mounted for downward and upward movement and disposed forward of the blade and having ground-engaging members, a tongue rigidly connected to the blade and extending forward therefrom and over the controlling truck, and an adjustable connection between the forward end of the truck and said tongue such that said tongue will move with the truck.

14. A leveler of the character described comprising a supporting frame, an arcuately curved blade mounted upon the frame for downward and forward swinging movement, a controlling truck mounted for downward and upward movement and disposed forward of the blade and having ground engaging members, a tongue rigidly connected to the blade and extending forward therefrom and over the controlling truck, an adjustable connection between the forward end of the truck and said tongue such that said tongue will move with the truck including a pin attached to the truck and extending upward through the tongue, a spring urging the tongue away from the truck, and means on the pin for forcing the tongue downward against the action of said spring.

In testimony whereof I hereunto affix my signature.

EDWARD OVERMAN.
